CLAIM

The ornamental design for a vehicle headlight, as shown and described.

DESCRIPTION

FIG. 1 is an elevational view of a right vehicle headlight (as viewed from the front of the vehicle, the left vehicle headlight being a mirror of the right and is not illustrated), the right vehicle headlight has a two horizontal louvers between the lens and reflector intersecting a vertical member separating two reflector chambers;

FIG. 2 is a right side elevational view of the vehicle headlight having a complex arcuate area adjacent the perimeter; and

FIG. 3 is a left side elevational view of the vehicle headlight; and

FIG. 4 is a top down plan view of the vehicle headlight illustrating the interior through the outer clear lens;

FIG. 5 is bottom up plan view of the vehicle headlight; and,

FIG. 6 is an elevational view of the vehicle headlight (as viewed from the rear of the vehicle), illustrating the Class B surface. This view is not claimed and is used for secondary filing.
